UNITED STATES PATENT OFFICE.

FREDERICK E. HILLIARD, OF BROOKLYN, NEW YORK, AND WALTER GOUGH STEVENS,
OF PALISADES PARK, NEW JERSEY.

APPARATUS FOR CUTTING AND POLISHING PRECIOUS STONES.

1,228,919.

Specification of Letters Patent.

Patented June 5, 1917.

Application filed May 19, 1916. Serial No. 98,508.

To all whom it may concern:

Be it known that we, FREDERICK E. HILLIARD and WALTER G. STEVENS, of the city of New York, borough of Brooklyn, New York, and Palisades Park, New Jersey, respectively, are the joint inventors of an Improvement in Apparatus for Cutting and Polishing Precious Stones, of which the following description, in connection with the accompanying drawings, is a specification, like letters and figures on the drawings representing like parts.

In the art of cutting stones, certain apparatus has been heretofore invented to permit the lapidary to present the stone to the lapidary's wheel at the proper angle to grind the facets uniformly and in proper number and arrangement.

One of these devices which has come into considerable use is shown in Patent #510,817 of December 12th, 1893, and our present invention is designed to be used with the parts A, B, C, b and C' shown in said patent.

The object of the present invention is to provide a device whereby the long-stick may be used exclusively, the short-stick being entirely dispensed with, whereby considerable time is saved in cutting a given number of stones and greater accuracy is attained. A further object is to provide a more simple and convenient means for spacing the step by step rotation of the stick into any number of even parts to accurately space the facets.

Referring to the drawings forming a part of this specification,

Figure 1. is a side elevational view of an apparatus embodying our invention.

Fig. 2. is an enlarged plan view, partly in section, of the hinge portion of the device and engaging portions of the spacing means.

Fig. 3. is a plan view of the hinge portion showing the means used to adjust the stiffness of the hinge.

Fig. 4. is an enlarged end view of one of the spacing elements.

Fig. 5. is an enlarged end view of one of the spacing elements used in conjunction with the element shown in Fig. 4.

Figs. 6 and 7 illustrate alternate or modified forms used instead of those shown in Figs. 4 and 5.

Fig. 8. illustrates a short and long stick-

holder respectively and about of full size as used commercially.

A³ indicates the top surface of a bench or table having a socket-piece A² attached thereto in which is rotatably held the rod B.

The lapidary's wheel P is carried by a suitable rotating shaft P'. The post B receives upon it the hub C of a head, the other part of the head being a bracket C'. By means of a screw C³ the hub C may be raised or lowered a pre-determined distance with relation to the wheel P. The screw C² holds the head C in adjusted relation on the post B.

b indicates a portion of the bracket C' and is calibrated with any desired number of sub-divisions as indicated by the lines C⁴. The parts so far referred to are commonly in use by lapidaries. Adjustably mounted on the portion b and clamped thereto by the lever and screw elements b' and b² is a hinge comprising the parts D—D' and D². The rod portion D² is provided with a screw thread d at one end which engages a thread formed in the element B² as illustrated and a shoulder d' is formed at the inner end of the thread d that abuts one side of the element D so that by turning the rod D² the element D can be forced against the surface d², thereby providing means to hold element D by friction to element D' to prevent it from rocking too freely in use. A jaw nut d³ holds the rod D² in its adjusted position.

The hinge element D is provided at one end with an even number of indents d⁴ arranged at equi-distant intervals apart and this element may be changed for one having a greater or less number of indents, so long as they are multiples of two and are spaced evenly apart. The stick-holder E is provided with a tooth E' which engages any one of the slots E² that are formed in the lower end of the co-acting element F herein-after referred to as the crown-piece, and these slots are spaced apart at pre-determined points to sub-divide the periphery of the crown-piece intermediate of the teeth f—f—etc., there being preferably but four of said teeth f so that they will mesh with any number of indents d⁴ formed in the element D, thereby making it unnecessary to have more than one crown-piece to engage any equal number of indents.

The crown-piece is provided with a cone-

shaped recess G' formed in the element D, and which serves as a guide in reinserting the crown-piece and also to perfectly adjust the parts in coöperative relation.

5 It will be observed that the entire length of the elements D and F is very short, in fact three quarters of an inch in length, and this reduction in the length of these elements permits of the use of the long-stick in grinding the outer row of facets since the total length of the device with the long-stick held in the stick-holder E is still short enough to reach a distance short of the wheel center when grinding, with the crown-piece in its 10 lowest position, which is not the case with the apparatus heretofore used and therefore it has been customary to first hold the jewel and fasten it in a long-stick to cut the inner facets, thus leading to inaccuracy in the cutting and loss of time in cutting a given number of stones. Figs. 6 and 7 show cone-shaped pins and holes in the coöperating parts while Figs. 4 and 5 show a different form but it is to be understood that any 15 proper forms may be used that will coöperate to effect the purpose.

It will be seen that the crown-piece can be removed and replaced in a very short space of time and any tooth f can be used as the 20 visible grinder and inserted opposite the desired number on the periphery of the element D and thereafter successively rotated as the facets are cut on the jewel.

Inasmuch as the stick-holder is grasped 25 and retained in the hand of the operator during the entire grinding or polishing operation, it follows that the operator adjusts

the pressure on the stone to the particular requirements of the stone, and in removing and replacing the crown-piece the friction 40 joints holds the hinge element or spacing device at a convenient angle to receive the crown-piece, as will be readily understood.

Having thus described our invention we claim as new,

1. The combination of a stick-holder having a crown-piece at one end provided with an even number of projections spaced at equal distances apart and provided with a central projection, and a spacing member 50 provided with a greater number of indents of even number and spaced an even distance from each other and adapted to engage with the teeth of the crown-piece, and provided with a central recess into which the projection on the crown-piece fits. 55

2. The combination of a stick-holder having a crown-piece at one end provided with a central projection, and a spacing device comprising a movable hinge element, a stationary hinge element, a rod provided with a thread at one end and a shoulder adjacent thereto which abuts one side of said movable elements to hold it in frictional contact with said stationary element. 60

Signed at New York in the county of New York and State of New York this 17th day of May A. D. 1916.

FREDERICK E. HILLIARD.
WALTER GOUGH STEVENS.
